APPARATUS FOR MAKING DIPPED GOODS

John R. Gammeter, Akron, Ohio

Application June 30, 1937, Serial No. 151,193

6 Claims. (Cl. 18—2)

This invention relates to apparatus for making dipped goods such as prophylactic rubber articles, finger cots, toy balloons, etc.

The general purposes of the invention are to provide an improved form conveyer for use in making dipped goods and to provide an improved device for rolling reinforcing rings or beads at the edges of the articles.

It has heretofore been proposed to provide a form conveyer which passes through various dipping and drying stations, a bead-rolling apparatus, a vulcanizer and a stripping station, but such conveyers have not been entirely satisfactory, and the bead-rolling operation has required highly accurate control on drying times, etc. because latex which is now quite generally used for making these goods, if too dry will not roll effectively in the bead. Variations in atmospheric conditions render such accurate control extremely difficult. Moreover by the apparatus heretofore used there is a tendency to build a twist into the bead which is objectionable in the goods after they are cured.

One object of the present invention is to provide a simple, effective conveyer mechanism for the forms.

Another object of the invention is to provide a simple, effective bead-rolling device in which such accurate control of drying under varying conditions is not required and in which there is no tendency to establish a twist in the bead which will be noticeable in the finally cured article.

The foregoing and other purposes of the invention are attained in the apparatus illustrated in the accompanying drawings and described below. It is to be understood that the invention is not limited to the specific form thereof shown and described.

Of the accompanying drawings:

Figure 1 is a plan view of apparatus embodying the invention.

Figure 2 is a front elevation thereof.

Figure 3 is a section on line 3—3 of Figure 1.

Figure 4 is an enlarged view partly in diametral section of a form and its mounting.

Figure 5 is a section on line 5—5 of Figure 1.

Referring to the drawings, the numeral 10 designates a flexible conveyer belt which may be of rubber, rubber and fabric, metal, leather or other suitable material arranged to be driven over suitable pulleys, (not shown) and over track or guide 11, which may be supported on standards 12, 12.

Secured upon belt 10 are cross bars 13 which preferably project from both sides of belt 10 and

having hinged on their opposite ends, mountings 14, 14 for rotatable form supports 15, 15. Mountings 14 carry pins 16 on which supports 15 are journaled and supports 15 have therein extension tubes 15^a which together with pins 16 on which they are journaled extend down into forms 17 which latter are secured upon supports 15 as by ferrules 18, the forms 17 adjacent their lower ends being secured on the lower ends of tubes 15^a which are journaled on the lower ends of pins 10 16. Pins 16 and extension tubes 15^a afford a strong structure supporting the forms 17 which usually are of glass, whereby the forms are effectively adapted for the bead-rolling apparatus to be described.

It will be understood that the forms 17 are caused by travel of belt 10 to go through the various dipping and drying stations until they pass to the bead-rolling apparatus herein shown at which they arrive usually depending vertically 20 downwardly from the belt 10. The belt 10 for apparatus for making prophylactic rubber articles of latex may travel at a rate of 12 feet per minute.

The bead-rolling apparatus comprises two rollers 20, 20 arranged along opposite sides of belt 10 and onto which the forms may be swung by rails 21, 21 engaging roller portions 15^b, 15^b of form supports 15. The rollers 20 preferably have a cushioning tube 22 of material such as sponge 30 rubber or printer's compound thereon over which may be applied a layer 23 of chamois or the like. For many years beads were rolled by hand and the material of these rollers approximates the softness of the fingers and gives a corresponding 35 rubbing action desirable to the operation of a bead roller of the type herein described. The forms are arranged to be swung upwardly and outwardly by rails 21 and to be gently laid upon bead rollers 20 upon which they rest by gravity. 40 Rollers 20 preferably support the forms substantially horizontally whereby the maximum weight of the forms and their mountings holds the forms under pressure against the bead rollers 20. This pressure may be varied by varying the height of 45 the bead rollers relative to belt 10 so that the forms rest thereon at various angles or by supplementing the pressure due to their weight by springs or pressure rails or other means.

Bead rollers 20 are set at an angle such that 50 at the entering end the forms 17 are contacted inwardly of the line to which the forms were dipped and at the exit end the forms are contacted to the required distance outwardly along the forms to roll the beads on the goods so as to 55

produce reinforced goods of predetermined length. This will be understood by skilled artisans.

The rollers 20 are preferably quite long (in a prophylactic machine as long as six feet) and are preferably rotated slowly (in a prophylactic machine with a surface speed of about 20 feet per minute) and the forms are caused to rotate about their own axes while resting on bead rollers 20 whereby the action of the bead rollers on the rubber deposits on the forms is substantially longitudinally of the forms at such a slight angle and at such relatively low speeds as to avoid setting up a twist in the beads or picking up or 15 tearing the deposited rubber, even under varying atmospheric conditions.

By revolving the forms by contact with the bead rollers by urging the rotatable forms against the bead rollers under pressure, while traveling 20 along in the machine, the use of a form-revolving mechanism as heretofore required is obviated and the rotation of the form is the natural rotation on the bead roller due to contact therewith with but slight relative movement at the 25 point of contact of the form which results in greater smoothness and uniformity in the beads.

At the exit end of the bead-roller rails 24, 24 are arranged to lower the forms back to the vertical positions in which they normally depend 30 from belt 10 ready to pass through final drier, vulcanizer, stripping station, etc., as will be understood.

The bead rollers 20 may be driven by chain and sprocket means 25, 25 driven by motors 26, 35.

Modifications of the invention may be resorted to without departing from the spirit thereof or the scope of the appended claims.

What is claimed is:

1. In combination, a conveyer having form-mountings hinged thereon, form supports rotatably supported on said mountings, forms carried by said form supports, a bead roller at a side of said conveyer, and means for lifting the forms onto said bead-roller whereby they may roll along on the bead-roller during travel of the conveyer and means for lowering the forms off the bead-roller, said bead-roller being so arranged with respect to said conveyer that the forms are carried by the conveyer into engagement with said roller so as to be solely rotated by contact with the roller as the forms are translated with respect to the roller by the conveyer.

2. In combination, a conveyer having form-mountings hinged thereon, form supports rotatably supported on said mountings, forms carried by said form supports, a bead roller at a side of said conveyer, and means for lifting the forms onto said bead-roller whereby they may roll along on the bead-roller during travel of the conveyer, said bead-roller being so arranged with respect to said conveyer that the forms are carried by the conveyer into engagement with said roller so as to be solely rotated by contact with the roller as the forms are translated with respect to the roller by the conveyer.

3. The combination in apparatus for making

deposited rubber goods of a conveyor having rotatable forms thereon, a rotatable roller associated with the conveyor so as to extend longitudinally thereof at an angle, and means for bringing said forms in succession onto said roller to be supported thereby and to translate said forms along the roller in contact therewith whereby the forms are caused to rotate on the roller solely by contact therewith during such translatory movement, said roller being adapted for progressively rolling deposited rubber on the forms upon itself to form beads on such rubber goods.

4. The combination in apparatus for making deposited rubber goods of a conveyor having rotatable forms thereon, a rotatable roller associated with the conveyor so as to extend longitudinally thereof at an angle, and means for bringing said forms in succession onto said roller under yielding pressure to be supported by said roller and to translate said forms along the roller in contact therewith whereby the forms are caused to rotate on the roller solely by contact therewith during such translatory movement, said roller being adapted for progressively rolling deposited rubber on the forms upon itself to form beads on such rubber goods.

5. The combination in apparatus for making deposited rubber goods of a conveyor having rotatable forms thereon, a rotatable roller associated with the conveyor so as to extend longitudinally thereof at an angle, and means for bringing said forms in succession into contact with said roller and to translate said forms along the roller in contact therewith whereby the forms are caused to rotate on the roller by contact therewith during such translatory movement, said roller being adapted for progressively rolling deposited rubber on the forms upon itself to form beads on such rubber goods, said roller being so arranged with respect to said conveyor that the forms are carried by the conveyor into engagement with said roller so as to be solely rotated by contact with the roller as the forms are translated with respect to the roller by the conveyor.

6. The combination in apparatus for making deposited rubber goods of a conveyor having rotatable forms thereon, a rotatable roller associated with the conveyor so as to extend longitudinally thereof at an angle, and means for bringing said forms in succession into contact with said roller under yielding pressure and to translate said forms along the roller in contact therewith whereby the forms are caused to rotate on the roller by contact therewith during such translatory movement, said roller being adapted for progressively rolling deposited rubber on the forms upon itself to form beads on such rubber goods, said roller being so arranged with respect to said conveyor that the forms are carried by the conveyor into engagement with said roller so as to be solely rotated by contact with the roller as the forms are translated with respect to the roller by the conveyor.
